SLIDING DOOR CONSTRUCTION FOR CORRUGATED CONTAINERS AND THE LIKE

Reginald H. Hodgson, Atlanta, Ga., and Frank W. Thomas, Baltimore, Md., assignors to Albemarle Paper Manufacturing Company, Richmond, Va., a corporation of Virginia

Filed Jan. 3, 1964, Ser. No. 335,611

7 Claims. (Cl. 222—561)

This invention has to do with large size containers, and relates more particularly to the provision of a sliding door opening by means of which the contents of the container may be readily dispensed.

While its utility is not so limited, the instant invention is particularly suited for use with large size corrugated paperboard containers in which as much as one thousand pounds or more of fertilizer or similar materials are packaged. Such large size packages are obviously extremely difficult to handle, and once the package has been placed on a farm truck or other vehicle, it is highly desirable for the user to be able to dispense the material directly from such vehicle without having to tear apart the container or repeatedly move it about or otherwise adjust its position.

Accordingly, a principal object of the instant invention is the provision of a sliding door assembly which may be readily associated with a large size container by the simple expedient of fitting such assembly in an opening in the container, the construction of the assembly being such that it will be held in place in the container by the weight of the contents which will serve to urge flange portions of the assembly into sealing engagement with the container walls in the areas immediately surrounding the opening therein.

A further object of the instant invention is the provision of a door assembly of the character described which is provided with a sliding door panel which may be readily and easily opened to permit the controlled discharge of the contents of a container with which the door assembly is associated.

Still a further object of the instant invention is the provision of a door assembly of the character described which is extremely sturdy and capable of withstanding considerable abuse, and yet is of relatively simple and inexpensive construction.

The foregoing, together with other objects of the invention which will appear hereinafter or which will be apparent to the skilled worker in the art upon reading this specification, we accomplish by those constructions and arrangements of parts of which we shall now describe certain exemplary embodiments.

Reference is now made to the accompanying drawings wherein:

FIGURE 1 is a fragmentary front elevational view illustrating the bottom portion of a conventional heavy duty corrugated container incorporating a door assembly in accordance with the instant invention.

FIGURE 2 is an enlarged fragmentary sectional view taken along the line 2—2 of FIGURE 1.

FIGURE 3 is an enlarged perspective view of a door assembly in accordance with the instant invention.

FIGURE 4 is an enlarged perspective view of a modified door assembly in accordance with the instant invention.

FIGURE 5 is a rear elevational view of the modification of the invention illustrated in FIGURE 4.

The container itself does not constitute a limitation on the instant invention, although for practical purposes it will comprise in most instances a corrugated paperboard structure having sufficient strength to adequately package the material being handled, whether it be fertilizer or

2

other comparable substances. Preferably the container will be of the type having a tubular body with closure flaps at the top and bottom ends thereof. Such a container is indicated generally at 1 in FIGURE 1 of the drawings, and the container will be provided with a rectangular opening 2 the bottom edge of which is essentially co-planar with the bottom wall 3 of the container. Fitted snugly within the opening is a door assembly, indicated generally at 4, which comprises a sliding door part 5 and a frame part 6.

The door part 5 is of rectangular configuration and is preferably formed from an essentially rigid material such as plywood, pressed board, or the like. Preferably it will be provided with a handle or knob 7 by means of which the door part may be readily opened and closed.

The frame part, on the other hand, is preferably fabricated from sheet metal, such as conventional steel strip, which is cut, formed and welded to provide a pair of opposing channels 8 and 9 which define the opposite sides of the frame. Side flanges 10 and 11 project outwardly from the channels 8 and 9, respectively, at their rearward edges; and similarly a top flange 12 projects upwardly from the upper edges of the channels. As will be evident, the flanges 10, 11, and 12 are essentially co-planar and, when the door assembly is fitted into the opening 2, the flanges are juxtaposed to the inner surfaces of the container wall in which the opening is formed, with the channels 8 and 9 projecting outwardly through the opening. In similar fashion, the frame part is provided with a bottom flange 13 which projects rearwardly from the bottom edges of the channels 8 and 9 and hence lies in a plane at essentially right angles to the channels 8 and 9 and the flanges 10, 11 and 12. The flange 13 thus overlies the bottom wall 3 of the container and coacts with the other flanges to retain the frame part in position.

As should now be evident, the door part 5 is adapted to slide vertically in the channels 8 and 9; and in this connection, it has been found desirable to line the channels 8 and 9 internally with guide tracks 14 and 15 which are generally U-shaped in cross section and of a size to just nicely receive the opposite side edges of the door part for sliding movement therein. The guide tracks may be formed from wood, plastic, or other material which will readily permit sliding movement of the door part. Such guide tracks have been found to be particularly desirable where the metallic frame part is coated with a plastic or resinous material by a dipping operation, such resinous or plastic coating serving as a protective covering for the metallic parts and acting to prevent corrosive attack by the contents of the container. Such expedient is highly desirable where fertilizers are being packaged since such materials can be highly corrosive to metallic surfaces. For example, after the metallic frame parts are fabricated, they are cleaned, primed, pre-heated, and then coated by being dipped in a bath of a plastic substance, such as Plastisol, which is a polyvinyl chloride resin dispersed in a liquid plasticiser along with colorants, stabilizers and other modifying agents, whereupon the coating is cured by heat. This treatment results in a continuous all-over protective coating enveloping the entire frame.

It will also be evident, particularly from FIGURE 2 of the drawings, that the dimensioning of the frame parts are such that when the frame is properly positioned in the opening in the container, the channels 8 and 9 will project through the opening with the innermost surface of the door part positioned to just clear the outermost surface of the container side wall. The door opening may be thus readily opened by sliding the door part 5 upwardly so that it assumes the position illustrated in dotted lines in FIGURE 2, in which position the contents of the carton will readily flow outwardly through the uncovered opening. Obviously, the door part may be sub-

sequently moved downwardly to close the opening and arrest the flow of contents.

Referring now to FIGURES 4 and 5 of the drawings, we have therein illustrated a modification of the invention wherein the opposing side members 16 and 17 of the frame part are not truly channel shaped, but rather have guide track engaging flanges 18 and 19 on their outermost sides against which the guide tracks 20 and 21 are seated. In this instance, however, the guide tracks are held in place by means of pairs of ears 21, 22, and 23, 24. The ears 21 and 22 are formed as an integral extension of a rearwardly directed flange 25 which is connected along its innermost side edge to the downwardly extending flange 26 which in turn is connected to the horizontally disposed flange 27. Actually, the entire frame structure is formed from a single strip of metal, with the exception of the strip 28 which is welded or otherwise secured to the bottom flange 13 and mounts the ears 23, 24 at its opposite ends, and the corner pieces 29 and 30 which extend between the side flanges 10 and 11 and the top flange 12. If desired, the strip 28 may be provided with an elevated sill portion 31 adapted to abut against the lowermost inside surface of the door part 5 when it is in the closed position. Such sill tends to prevent leakage of the contents from beneath the door opening. As before, it is preferred that the entire frame be coated with a covering of protective plastic or the like.

As should now be evident, the door assemblies of the instant invention provide a sturdy, yet easily installed means for dispensing controlled quantities of material from a large size container utilizing containers which are of conventional construction.

Having thus described our invention in certain exemplary embodiments, and with the understanding that modifications may be made therein without departing from its spirit and purpose, what we desire to secure and protect by Letters Patent is:

1. In a container having enclosing body walls, an opening formed in one of said body walls adjacent the bottom wall of said container, a door structure in said opening comprising a frame part having outwardly projecting top and side flanges positioned to make face-to-face contact with the inner surfaces of the body wall in which said opening is formed, a flange projecting inwardly from the bottom of said frame in face-to-face contact with the inner surface of said container bottom wall, said frame part having a pair of oppositely directed vertically disposed channel members projecting forwardly through said opening at the opposite sides thereof and acting to define door receiving guides lying immediately beyond the outer surface of the said body wall in which said opening is formed, and a door panel slidably received in said channel members for opening and closing the opening in said container.

2. In a container having enclosing body walls, an opening formed in one of said body walls adjacent the bottom wall of said container, a door assembly in said opening comprising a frame part having outwardly projecting top and side flanges positioned to make face-to-face contact with the inner surfaces of the said body wall in which said opening is formed, a flange projecting inwardly from the bottom of said frame part in face-to-face contact with the inner surface of said container bottom wall, said frame part having a pair of oppositely directed vertically disposed channel members projecting forwardly through said opening at the opposite sides thereof, guide tracks mounted in said channel members for slidably receiving a door panel, said guide tracks being positioned so as to receive a door panel with the inner surface of said door panel positioned to just clear the outer surface of the said container wall in which the opening is formed, and a door panel slidably received in said guide tracks.

3. The structure claimed in claim 2 wherein said channel members are U-shaped in cross section, and wherein said guide tracks are of a size to be snugly received within said U-shaped channels.

4. The structure claimed in claim 2 wherein said channel members each have a flange along one side edge, and wherein said guide tracks are secured in said channels by means of bendable ears positioned adjacent the upper and lower extremities of said guide tracks at the sides thereof opposite said flanges.

5. The structure claimed in claim 2 wherein said frame part, exclusive of said guide tracks, is covered in its entirety with a plastic material, whereby to render said flange structure impervious to corrosive attack by the contents of the container.

6. A door assembly for use in conjunction with a dispensing opening having its bottom edge lying along the bottom wall of a container, said door assembly comprising a frame part and a door part, said frame part having outwardly projecting top and side flanges and a rearwardly projecting bottom flange, vertically disposed frame-forming members projecting forwardly from the inner side edges of said side flanges, guide track means mounted on said frame members and positioned to slidably receive a door forming panel, and a door forming panel slidably received between said guide tracks.

7. The structure claimed in claim 6 wherein said frame part at least is formed from metal completely covered with a non-metallic protective covering of imperforate character.
